TITUS ANDREW BEECHER, OF TAFT, CALIFORNIA.

METHOD FOR LOCATING THE PLACE AND CHARACTER OF A LIQUID COMING FROM STRATA IN A WELL.

1,090,673.

Specification of Letters Patent. Patented Mar. 17, 1914.

Application filed October 1, 1912. Serial No. 723,271.

To all whom it may concern:

Be it known that I, TITUS A. BEECHER, a citizen of the United States, and a resident of Taft, in the county of Kern and State of California, have invented a new and Improved Method for Locating the Place and Character of a Liquid Coming from Strata in a Well, of which the following is a full, clear, and exact description.

10 This method has for its object the determination and location of strata containing liquids when drilling a well or in a drilled well.

15 To carry out the above stated object, I employ proper coloring matter, placed in a predetermined position in the well, and then the liquid from the well is gradually discharged and analyzed to ascertain if the so discharged liquid contains the coloring matter.

20 It is a well known fact in the oil fields that the water contained in strata above the layers containing the oil must be positively shut off from access to the well to make this well exploitable for the oil. The presence 25 of water in the oil degrades the quality of the oil extracted from it, and, due to the existence of gases, the oil is emulsified in the water and expensive methods are necessary for the separation of the oil from the water. But not only is the presence of water 30 dangerous to this particular well in which the water stratum is leaking but it is generally drowning the oil out from the oil strata intersected by this particular well, and consequently it is injurious to the entire oil field. There are many methods for preventing leakage of water from upper layers 35 into the oil strata, the most commonly employed being cementation of the foot of casing passed below the water layers and resting above the oil strata. But there is no method for positive assurance that the cementation is perfect and no leak between 40 the shoe casing and the ground exists. It must also be remarked that in well drilling the boring master's journal or diary will generally give the depth of stratum from the surface and the thickness of the same, but

45 50 anybody acquainted with well boring knows that is only close approximation. Where few strata are intersected, as the general practice is, without placing a casing for each intersected stratum containing liquid

(which would be expensive and would reduce the diameter of the well so that it would become unexploitable), it is impossible to say what this stratum contains, as there is generally a liquid already in the well.

55 60 In wells where oil strata are flooded by water no oil can be extracted until the water is shut off from same. It is not known where the water enters into the well and in what particular places, but the importance 65 of shutting off the water from oil strata is so great to the oil fields that States where oil fields exist have enacted laws imposing a heavy penalty for allowing water to enter oil strata.

70 75 It is easily seen that before the water can be shut off it must be definitely known whence this water comes and to determine exactly the location and the character of the stratum that supplies the water, I have designed a method by means of which the character and the depth of the stratum supplying the liquid may be positively established. Also when a water stratum is cemented or plugged in a well by the same method 80 it may be ascertained as to the condition of the plug or cementation, that is, if a leak exists or not. While my method is primarily designed for the purpose of shutting off the water strata from the oil layers, the same 85 method may be used for shutting off water strata of the upper ground from water strata lying in the lower grounds, or for separating mineral layers of water from ordinary water, etc.

90 Reference is to be had to the accompanying drawings forming a part of this specification, in which similar characters of reference indicate corresponding parts in all the views, and in which—

95 100 Figure 1 is a section through a drilled well showing the different strata and illustrating my method; Fig. 2 is the container for the coloring matter and the means for smashing the same to force the coloring matter out of the container; and Fig. 3 is the application of my method to a well during the process of drilling.

105 Referring to Fig. 1, the well is shown to intersect layers supplying water and oil. No definite information could be gotten from the well on the surface as to where the water came from, as cementation of the shoe

casing 10 was made after the casing 11 was forced below the known water strata. The fact that an oil stratum 13 was intersected was established. The fact that oil was present in the well, the boring was continued until a new stratum 14 was intersected and even farther, until it was established that water existed in the well. Now where that water comes from it is impossible to tell.

10 Is it from an intersected stratum 14 or from the upper strata leaking behind the shoe casing 10 or from the lowermost portion of the latter which may have crevices and that the water may leak through? To determine this I take a container A, preferably in the form shown in Fig. 2, and made of sheet metal that can be easily smashed. The container is provided at its upper part with a plug A'. The plug being removed the coloring matter, in liquid or solid form, is introduced into the container, and then the plug A' is replaced, making the container liquid proof. The container is attached by means of a suspension member A² to an S-member

15 B, which in turn is suspended from any boring implement by means of which the container is smashed in the desired place. The whole is lowered by means of a cable D until the bottom of the well is reached. The formation of the bottom and between the strata containing the liquids may be, as is general in oil fields, of shale, slate or limestone. The container reaching the bottom of the well, which may be of the formation

20 30 35 40 45 50 55 60 65 70 75 80 85 90 95 100 105 110 115 120 125 130

above stated and supposed not to contain any liquid, is smashed in this formation by means of the boring implement C with as little disturbance as possible. The coloring matter escaping from said container due to its rupture will dissolve and hydraulize in the liquid. The boring implement is then hoisted out of the well. It must be remarked that, as in all wells, a natural level of liquid exists in these, and by pumping out or bailing out the liquid from the surface of said well the same is continuously maintained from the sources of formations containing the liquids. As shown in Fig. 1 the formation that will supply a liquid is only the thirteenth, or the one below it, the fourteenth. The coloring matter being dissolved below this, and, as above stated, with little disturbance during the smashing of the container, little diffusion will take place and the coloring matter will not rise to the stratum 14. In bailing the water or pumping the same from the top of the well, the same will be replaced by the stratum 13 and consequently no coloring matter will be carried up by the flow from the strata. That proves that no liquid is coming from the lowermost portion of the well, that is, below the stratum 14. After this is determined a bridge 15 is placed in the well, approximately a little below the lower portion of

the stratum 14 so as to shut off the formation which lies below the stratum 14. Again, a new container with coloring matter is in the same way lowered into the well and smashed on this bridge 15, so that the coloring matter will dissolve in the liquid, and by bailing the liquid from the top or pumping the same, the stratum 14 will supply liquid to the well and force the coloring matter to the top, where it will be either pumped up or bailed out after awhile. By the color of the water or by analysis, which may be characteristic of the coloring matter used, it can be proved that the liquid is supplied from this particular stratum. It must be pointed out here that the coloring matter used may be such as dissolves in water and oil or hydraulizes only in water and having a specific gravity a little above 1. The importance of having coloring matter in some cases that will not combine with the hydrocarbons of the oil is that when the water is mixed with oil, a partial separation of the water and the oil can be obtained by leaving the same in a test tube, where the difference in the gravity of the two liquids will separate them partially and the coloring matter contained in that mixture will remain in the water and not combine or hydraulize in the oil. After the tube has been smashed on the bridge 15, the coloring matter will be carried up by the inflowing liquid when the liquid level in the well is lowered by bailing or pumping. The coloring matter employed in this particular case may be such as to combine only with water, as above stated. If the liquid flowing from the stratum 14 is not water it may carry up the coloring matter to the upper surface and not combine with the same, thus while this would indicate a liquid stratum, the nature of liquid would have to be determined by a different coloring matter that would form a characteristic color with oil, for example, or form a peculiar solution, the character of which might be easily detected by a chemical or spectra analysis. If the mixture so analyzed has been proved to be water, the latter must be shut off or plugged.

To plug the water, as it is commonly done in oil fields, a plug 16 is formed of wood, or lead, or Manila rope, or any other suitable material, in a formation such as shale, slate, limestone, or any other formation excepting an oil or water stratum. The location of the water stratum being found by the length of the cable and boring implement and the container, the position of this plug is easily determined from the boring diary of the well, giving the depth and the thickness of the layer approximately. After the plug 16 has been inserted into the well in the desired stratum, it must be insured that there is no leakage from the stratum 14 through this plug into the well above said plug. Again,

a container with coloring matter is smashed in a similar manner to that described, the liquid is bailed out to insure no flow from this particular part, and as the liquid supplied from the stratum 13 is oil, the coloring matter placed above the plug 16 will not be carried up, as the flow is above the coloring matter. As the stratum 13 is known from the boring diary to be an oil stratum there is no necessity to ascertain the character of the same, and consequently there must be assurance that there is no leakage behind the shoe casing and the ground near the same from the water strata above said shoe casing. To find out that there is no leakage another plug 17 is placed in the ground, above the stratum 13, which may be a formation of shale, slate or limestone. Again, on the bridge 17 test is made by sending the container with coloring matter in the way above described, and releasing same above plug 17 to ascertain that no oil is passing through the stratum 13. As previously stated, when bailing the water up, if a liquid exists between the plug 17 and the stratum 13, the oil will carry the coloring matter up and while not mixing with the same, the matter may be detected in the bailing out of the water above the plug, and, if no leakage exists from the stratum 13, the coloring matter during the action of bailing will not rise to the surface or to the normal level of the well. After this has been ascertained another plug may be placed exactly below the place of cementation of the shoe (not shown in the drawing) and then a test performed again, and if leakage should exist the water flowing between the cementation and the shoe from the water strata above will force the coloring matter up while bailing the water out in the casing. After these tests have been made and it has been assured that no leak exists between the shoe casing and the ground, the plug 17 and the other plug placed above (not shown) may be drilled through until the stratum 13 is reached. Here, again, a new test can be made by employing special coloring matter which will dissolve in oil so that when bailing out a test can be made to prove that the oil is coming and lying in this particular stratum, and the well may be exploited without fear of being drowned by water as the lower and the upper strata have been positively proven to be shut off.

In drilling a new well when a liquid stratum is passed it can be ascertained directly by the method above described, that is, by sending a coloring matter in the well in the way of the stratum from where the liquid comes, to ascertain the character of the liquid. As the general practice is, a casing follows the boring, and by forcing the casing below that water stratum, the foot of the casing may be cemented so as to prevent

leakage into the well. By placing a bridge below the shoe and making a test as above described it may be ascertained that there is no flow into the well. The drilling is then continued until another stratum of liquid is reached, another test is performed in a similar way, and if, for example, the following stratum is a water stratum, the casing is forced below this stratum and cemented again, after it is ascertained that there is no leak behind the shoe casing and the ground. If the casing cannot be forced below this stratum a new casing may be placed, as it is generally done, and the stratum shut off from the well by cementation or any other method desired, the same being assured by a test in the way above described. Then the boring is continued until a third stratum is intersected supplying a liquid. If this stratum is supplying oil, the coloring matter used while not dissolving in the same would be carried up when bailing the well, and consequently can be either chemically or mechanically analyzed in the oil. A special coloring may be used, when in doubt, that will dissolve in the oil, but will form a particular mixture or give a characteristic chemical action that will distinguish the existence of the oil in the well.

In the case of drilling a well for mineral water, the same methods may be employed as in drilling wells for oil except that a special coloring matter may be used for determining the character of the mineral water, which may be hydraulized in said mineral water, or form a characteristic mixture which can be detected by a test. The coloring matter may be anilin dyes, vegetable or mineral matter, and will be characterized by their color in water, or will give a characteristic chemical reaction when certain chemicals are used for the test.

It is again pointed out that the method consists principally in placing the coloring matter in the desired place in the well, and by bailing the liquid out of the well, the coloring matter, when placed in the path of a liquid flowing from a stratum, will be carried up by the said liquid to the normal level of the well, where it is bailed out and a test made. The character of the liquid and the depth from the surface of the same may be found by measuring the length of the cable and by the implements used, as described before.

When tests are to be made one after another in the same plug, different colors may be employed for distinction.

Having thus described my invention, I claim as new and desire to secure by Letters Patent:

The method of ascertaining the character and location of liquid flowing into a well, which consists in placing coloring matter near the supposed path of the inflowing

liquid, then discharging from the well the portion of the liquid above the point at which the coloring matter is placed whereby the coloring matter, if in the path of the inflowing liquid, is forced to the discharge of the well by the inflowing liquid rising to the said discharge, and thereby the location of the inflow is determined, substantially as described.

In testimony whereof I have signed my name to this specification in the presence of two subscribing witnesses.

TITUS ANDREW BEECHER.
